FLAP RETAINING DEVICE FOR CARTONS

Robert S. Bloomer, Sr., Newark, N. Y., assignor to Bloomer Bros. Company, Newark, N. Y., a corporation of New York

Application April 5, 1954, Serial No. 420,920

7 Claims. (Cl. 229—7)

This invention relates to devices for retaining or holding in desired position the closure flaps of cartons, and more particularly, to retaining devices adapted for use with cartons such as those made of cardboard and other similar stock, which are often used for the bulk packaging of ice cream and other frozen comestibles, one object of the present invention being to provide an improved retaining device having a practical and efficient construction which may be readily and economically manufactured.

This invention is particularly suited for use with the type of cartons which are designed to be opened at one end for the removal of the contents by scooping or dipping. Such cartons are usually formed with a plurality of end closure flaps which are folded into overlapping position thereby forming a multilayer end closure for the carton. Specifically, the above invention is particularly well suited for use with the type of carton disclosed in the patent to William H. Inman and Raynor M. Holmes, No. 2,655,304, issued October 13, 1953.

Although the above carton has a novel automatic self-erecting bottom closure, and the carton may be opened by tearing action along a connection between adjacent side walls, the top end of the carton is closed by four separate flaps which are individually swung to closed positions and which may be opened independently of the side closure or the automatic bottom closure, for allowing removal of the contents by dipping or scooping. It is to this type of non-automatic end closure to which my invention is particularly adapted, for in many cases the consumer prefers to open the carton at the end and remove the contents by scooping, rather than separating the side walls of the carton and exposing the entire contents for removal by slicing.

In the above type of non-automatic end closures, there are at least three, and more often four, separate closure flaps which have to be swung from their overlapping closed positions upwardly to positions substantially coplanar with the respective side walls, and then downwardly against the outside of the carton side walls. When this is done the end of the carton is left fully exposed and the contents may be readily removed. However, heretofore this procedure has not been entirely satisfactory, because when the flaps are folded back against the respective side walls and then released, they tend to spring back to partially closed positions overlying the end of the carton due to the natural resiliency of the cardboard material of which the carton is made. As it is not possible for the consumer to hold all of the flaps down with one hand while scooping out the contents with the other, the result normally has been that two or more of the flaps have been allowed to spring back up partially covering the end of the carton and the consumer has removed the contents as best he could while trying to avoid coming into contact with the upwardly extending flaps. Usually one or more of the end flaps has a thick layer of the carton contents adhering thereto so that the consumer usually

2

got this material on his arm or on the sleeve of his garment. Not only is the above procedure unpleasant and unsatisfactory, but the carton flaps are liable to become contaminated by contact with the arm or sleeve of the consumer thereby producing an unsanitary condition when the carton is reclosed.

Another object of the invention is, therefore, to provide an improved retaining device or band for holding certain of the end closure flaps of the carton in downwardly extending positions so as to completely expose the end of the carton and to insure that the flaps will be out of the consumer's way during the removal of the contents of the carton.

Difficulty has also been experienced in the past in attempting to accurately remove the contents of the carton by means of a scoop or the like without the use of a second instrument, and without requiring the use of both hands. That is, because there is no rigid sharp edge adjacent the top of the carton there is no means for effectively removing the excess ice cream from the scoop, and thus no means for insuring uniform portions. The only satisfactory method heretofore has been to use a second instrument, such as a knife or the like and draw the same across the open end of the scoop to remove the excess contents clinging thereto. This, of course, requires the use of both hands and takes more time and effort than is desirable.

Another object of the invention is, therefore, to provide a flap retaining band of the above nature, which provides a rigid and well defined edge against which the scoop may be scraped to remove the excess therefrom and to assure uniform portions.

Another object is to provide a retaining band having the above advantages which is provided with means for facilitating the quick and easy resealing of the carton.

A further object is to provide a retaining band of the above nature which is simple in operation and which may be readily and economically manufactured and assembled.

To these and other ends the invention resides in certain improvements and combinations of parts, all as will be hereinafter more fully described, the novel features being pointed out in the claims at the end of the specification.

In the drawings:

Fig. 1 is a perspective view showing three of the end closure flaps of the carton held in position against the respective side walls by a retaining band employing the present invention;

Fig. 2 is a reduced top plan view, partly broken away, showing one of the end flaps in engagement with the retaining band for closing the end of the carton, and

Fig. 3 is a fragmentary sectional elevation substantially along the line 3—3 in Fig. 2.

The preferred embodiment of the present invention herein disclosed by way of illustration, preferably comprises a band shown generally at 10 which is adapted to closely fit the outside surfaces of an end of a carton shown generally at 11.

As more fully described in the above patent, carton 11 comprises four side walls 12, 13, 14 and 15, which are foldably interconnected as shown. A securing flap 16 is hingedly connected to side wall 12 and is glued to the outer edge of adjacent wall 13. End closure flaps 17, 18, 19 and 20 are hingedly connected to the upper edges of walls 12, 13, 14 and 15, respectively, as shown in Fig. 1. Flap 19 is substantially rectangular and is adapted to close the upper end of the carton as shown in Fig. 2. Flap 17 is preferably somewhat smaller than flap 19 while flaps 18 and 20 are provided with mating tongue and slit locking means. The carton is so designed that flap 19 is first folded into position closing the end of the carton and into direct contact with the contents thereof, while flap 17 is

thereafter folded over flap 19. Locking flaps 18 and 20 are then folded over flaps 19 and 17 and interlocked, as well understood in the art, and as more fully described in the above patent.

Band 10 preferably comprises four body members 21, 22, 23 and 24 of metal, plastic or other suitable material, which are interconnected adjacent the ends thereof for forming a substantially rectangular hollow frame, as shown in Fig. 1.

Body members 21, 22, 23 and 24 are not of uniform depth for the full length thereof, but the center of the lower edge of each member is arched upwardly, as at 25 (Fig. 1) to accommodate the bulging of the side walls caused by the expansion of ice cream as it is frozen. The end portions of the lower edge of the body members are flared outwardly, as at 26, for guiding the frame over the end of the carton.

Body members 21, 22 and 24 are preferably turned or flared inwardly along the upper edges thereof to form flanges 27, 28, and 29, respectively, as shown in Fig. 1, which extend inwardly at substantially right angles to the respective body members. Flange 27 is adapted to engage the hinge connection between side wall 12 and respective end flap 17, when flap 17 is swung to its downwardly extending position shown in Fig. 1. Similarly flange 28 engages the hinge connection between side wall 13 and end flap 18 while flange 29 engages the hinge connection between side wall 15 and end flap 20. Flanges 27, 28 and 29 arrest the downward movement of band 10 and serve to hold the same in position on the carton while at the same time they provide rigid and sharp edge portions against which the ice cream scoop may be scraped to remove the excess ice cream therefrom. Body member 23 is preferably not provided with a flange similar to flanges 26, 27 and 28, for flap 19 preferably is not held in depending position against side wall 14, but rather flap 19 is allowed to project upwardly through retaining band 10 and is free to be folded downwardly against the outside of the band, or folded across the exposed end of the carton, as hereafter more fully described.

As flap 19 is not confined by band 10, it may be folded downwardly along the outer edge of the band, as shown in dotted lines in Fig. 1 for completely exposing the end of the carton and allowing easy removal of the contents thereof. In addition, flap 19 may be folded forwardly to its position shown in Fig. 2, substantially closing the opposite end of the carton and thereby providing a temporary closure for the carton so that it may be returned to the refrigerator or freezer. Frame 10 is provided with means comprising a pair of spaced lip portions 30 (Fig. 1) for holding flap 19 in position for closing the end of the carton. Lip portions 30 are adapted to engage the free edge of flap 19 and are preferably formed from body member 21, although they could equally well be formed from body members 22 and 24. Lip portions 30 engage the upper or outer surface of flap 19 and hold the flap down in engagement with band 10 for providing a quick and effective means for reclosing the carton.

Thus it will be seen that my retaining band may be quickly positioned on the carton by merely opening the end closure flaps in the normal manner, then slipping band 10 downwardly over flap 19 and into engagement with flaps 17, 18 and 20 which have been swung from their closed positions to partially dependent positions along the outside of the respective side walls. As the lower flared portions 26 of band 10 engage flaps 17, 18 and 20 they force the same downwardly into engagement with the respective side walls at the same time that the band is being moved downwardly along the open end of the carton to its position shown in Fig. 1. The downward movement of the band is arrested by inwardly extending flanges 27, 28 and 29. In this position, three of the end closure flaps are securely held in out-of-the-

way positions while the remaining flap 19 may be readily swung downwardly and held in its downward position against carton wall 14 by the consumer as he steadies the carton for removal of the contents by scooping. However, it is not necessary that flap 19 be held, because it can be bent downwardly to such an extent that it will remain in substantially vertical position. Even if flap 19 extends partially over the open end of the carton it need not interfere with the removal of the ice cream because the other three flaps are out-of-the-way, and it is a simple matter to dip into the carton without coming into contact with flap 19.

After a sufficient portion of the contents has been removed, the carton may be readily reclosed without removing retaining band 10 and without necessitating the re-engagement of locking flaps 18 and 20. This is accomplished by merely swinging flap 19 across the open end of the carton and slipping the free edge thereof under lips 30. When in this condition, the carton may be returned to the refrigerator or freezer for reopening at a later date.

It will thus be seen that my invention provides a novel retaining band for holding a plurality of the carton end closure flaps in out-of-the-way positions against the respective sides of the carton for allowing free and unobstructed access to the contents of the carton. Moreover, my retaining band provides means whereby the carton may be quickly and easily reclosed by only a single end closure flap without disturbing the down-folded positions of the remaining closure flaps. In addition, my retaining band provides rigid and sharp edge portions extending inwardly over the open end of the carton against which the scoop may be scraped to remove the excess contents therefrom, the excess material dropping back into the carton. My band does not disfigure or require the mutilation of the carton, and it may be conveniently and easily slipped into place or removed when the carton is emptied, or when it is desired to completely reclose the partially full carton.

In view of the above, it will be seen that my invention accomplishes its objects and while it has been herein disclosed by reference to the details of a preferred embodiment, it is to be understood that such disclosure is intended in an illustrative, rather than a limiting sense, as it is contemplated that various modifications in the construction and arrangement of the parts will readily occur to those skilled in the art, within the spirit of the invention and the scope of the appended claims.

I claim:

1. The combination comprising a flap-retaining band and a carton of the type having a plurality of side walls, end closure flaps hingedly connected to the respective side walls of the carton and foldable over the open end of said carton for forming a multi-layer closure therefor, said band being detachable and comprising a plurality of body members, each of said body members extending at substantially right angles to the adjacent ones of said members for forming a substantially co-planar hollow frame, said members being adapted to closely engage certain of said end closure flaps when said flaps are folded back along the outside of the respective side walls of said carton for holding said flaps against said side walls in said folded positions, certain of said body members each having an inwardly extending flange adjacent the upper edge thereof for engaging the inside of the hinge connection between said end flaps and the respective side walls of the carton for holding said band in position on said carton with one of said flaps projecting outwardly through said band and being free therefrom for swinging movement to temporarily close said open end of said carton, and means on one of said body members spaced from the hinge connection between said free flap and the respective side wall of the carton for releasably engaging said free flap and holding the same in carton closing position.

2. The combination as specified in claim 1 in which said means on said band for holding said free flap comprises an inwardly extending lip portion on one of said body members.

3. The combination comprising a flap-retaining band and a carton of the type having a plurality of side walls, end closure flaps hingedly connected to the respective side walls of the carton and foldable over the open end of said carton for forming a multi-layer closure therefor, said band being detachable and comprising a plurality of body members, each of said body members extending at substantially right angles to the adjacent ones of said members for forming a substantially co-planar hollow frame, said members being adapted to closely engage certain of said end closure flaps when said flaps are folded back along the outside of the respective side walls of said carton for holding said flaps against said side walls in said folded positions, certain of said body members each having an inwardly extending flange adjacent the upper edge thereof for engaging the inside of the hinge connection between said end flaps and the respective side walls of the carton for holding said band in position on said carton with one of said flaps projecting outwardly through said band and being free therefrom for swinging movement to temporarily close said open end of said carton, and a plurality of inwardly extending lip portions on said body members spaced from the hinge connection between said free flap and the respective side wall of the carton for releasably engaging said free flap and holding the same in carton closing position.

4. The combination comprising a flap-retaining band and a carton of the type having a plurality of side walls, end closure flaps hingedly connected to the respective side walls of the carton and foldable over the open end of said carton for forming a multi-layer closure therefor, said band being detachable and comprising four body members connected together adjacent the ends thereof for forming a substantially rectangular co-planar hollow frame, said members being adapted to closely engage certain of said end closure flaps when said flaps are folded back along the outside of the respective side walls of said carton for holding said flaps against said side walls in said folded position, certain of said body members each having an inwardly extending flange adjacent the upper edge thereof for engaging the inside of the hinge connection between said end flaps and the respective side walls of the carton for holding said band in position on said carton with one of said flaps projecting outwardly through said band and being free therefrom for swinging

movement to temporarily close said open end of said carton, and means on one of said body members spaced from the hinge connection between said free flap and the respective side wall of the carton for releasably engaging said free flap and holding the same in carton closing position.

5. The combination as specified in claim 4 in which the body members of said band are flared outwardly adjacent the lower edges thereof.

6. The combination as specified in claim 5 in which said means on said band for holding said free end flap comprises an inwardly extending lip on one of said body members.

7. The combination comprising a flap-retaining band and a carton of the type having a plurality of side walls, end closure flaps hingedly connected to the respective side walls of the carton and foldable over the open end of said carton for forming a multi-layer closure therefor, said band being detachable and comprising four body members connected together adjacent the ends thereof for forming a substantially rectangular co-planar hollow frame, said members being flared outwardly adjacent the lower edges thereof and being adapted to closely engage certain of said end closure flaps when said flaps are folded back along the outside of the respective side walls of said carton for holding said flaps against said side walls in said folded position, certain of said body members each having an inwardly extending flange adjacent the upper edge thereof for engaging the inside of the hinge connection between said end flaps and the respective side walls of the carton for holding said band in position on said carton with one of said flaps projecting outwardly through said band and being free therefrom for swinging movement to temporarily close said open end of said carton, and a plurality of inwardly extending lip portions on said body members spaced from the hinge connection between said free flap and the respective side wall of the carton for releasably engaging said free flap and holding the same in carton closing position.
